BASKETBALL BANKBOARD SUSPENSION

Paul V. Townsend, Anderson, Ind., assignor to Recreation Equipment Corp., Anderson, Ind.

Application September 5, 1956, Serial No. 42,836

Term of patent 14 years

(Cl. D34—5)

The single figure is a front perspective view of a basketball bankboard suspension, showing my new design.

The broken line showing is for illustrative purposes only.

I claim:

The ornamental design for a basketball bankboard suspension, as shown and described.
